STOKER

Fredrick H. Fridenstine, Ogden, Utah

Application September 10, 1935, Serial No. 39,902
Renewed November 6, 1939

1 Claim. (Cl. 110—45)

My invention relates to stokers and has for its object to provide a new and efficient stoker for feeding coal into furnaces, which stoker is simple in construction, economically manufactured, and which will be highly efficient with the greatest benefit being low operating and upkeep costs.

A still further object is to provide a stoker which will be provided with a positive chain drive reduction gear with a belt drive from the motor to the reduction housing and with the fan of the device operating on one side of the box on the same shaft which drives the reduction gears and chain reducers in the box.

These objects I accomplish with the device illustrated in the accompanying drawings in which similar numerals and letters of reference indicate like parts throughout the several views and as described in the specification forming a part of this application and pointed out in the appended claim.

In the drawings:

Figure 1 is a side elevation of the stoker complete, ready to install in a furnace.

Figure 2 is a plan view of the stoker with the furnace shell and fire pot shown diagrammatically.

Figure 3 is a rear end view of the stoker.

Figure 4 is a side elevation of the fire pot of the stoker.

Figure 5 is a side view of the tuyère casting.

Figure 6 is a vertical section of the part shown in Figure 5.

Figure 7 is a vertical diametrical section of the fire pot, air chamber, and feed pipe.

Figure 8 is a plan view of the feed pipe and means of feeding coal into the feed screw from the hopper.

Figure 9 is a plan view of the base casting of the air chamber.

Figure 10 is a side elevation of the part shown in Figure 9.

Figure 11 is a plan view of the cover for the end of the air chamber.

Figure 12 is a side elevation of the part shown in Figure 11.

In the drawings of my stoker, the hopper is shown as A, the blower fan as B and the fire pot as C.

The fire pot for the stoker consists of a rectangular box-like base 5 forming the air chamber 6 therein, and with one side of the box-like base forming an extended end 7 on the same plane but at a slight angle to the parallel sides thereof to form a means for connecting the feed pipe, the

air pipe, and the clean out therein. The top surface of this extended end 7 is formed on a slope increasing in height from the outside of the end 7 to where it merges into the sides of the base 5. The lowermost portion of this slope is closed by a vertical wall and in said wall there are semi-circular openings 10, 11, and 13, into which the pipes for feeding coal, air, and for cleanout are placed. The clean out pipe 12 which is used for cleaning out the air chamber when accumulated fly ash and dust makes such cleaning necessary, is introduced in the semi-circular opening 13 and is provided with an end cap or closure 12a for holding the pipe closed until such cleaning is needed. A cover 15 is provided for the end 7 to cover the top thereof. To seal the end on the underside of the end piece of the cover there are like semi-circular openings 16, 17, and 18 to fit around the top portions of the air feed pipe, the fuel feed pipe, and the clean out pipe. With this construction, the air feed pipe 9, the fuel pipe 8, and the clean out pipe 12, are all on the same horizontal plane level with each other but, with the clean out pipe extending out at an angle to the fuel and air pipes, which are parallel to each other. The air pipe for the device consists of a hollow tubular pipe 9 leading from the blower fan B. A control valve 19 is carried in this pipe 9 to control the flow of air therethrough. The other end of the pipe 9 is open to the interior chamber 6 of the base casting 5. In this base the fuel fire pot 20 is carried supported on the bottom by a boss 21 with a set screw secured through the bottom of the base 5 into the boss to hold the fire pot always aligned and in position in the air chamber. The fire pot extends up in an inverted frusto-conical pyramidal pot 22 to above the level of the base 5 and the top end of the pot 22 is flanged outwardly at 23. Onto this flange I then set my tuyère casting 25 which consists of a flat top portion formed preferably square to fit onto the top of the pot 22 and on the underside of this flat top portion 26 I provide spacer bosses or lugs 27 to provide a tuyère opening entirely around the four sides of the central square 28 and allow the air from the air chamber to pass through this opening to ignite the fuel forced up through the pot 22. The sides of the tuyère casting are sloped out to make the tuyère casting from side view in the form of a frusto-pyramidal casting and these sides engage the top sides of the air chamber base 5 and close the top thereof.

The fuel feed pipe 8 is set and formed integral with the side of the pot 22 and extends out

- through the opening 10 in the base and the cover to the source of fuel which will be later described and this pipe is provided with an anti-back smoking feature by cutting a section 30 from the 5 pipe on three sides thereof and bending this section up from the pipe to leave an opening 31 therethrough with the section 30 so bent that the air from the air chamber will pass into the coal pipe 8.
- 10 The coal feed pipe 8 has a flange on the end thereof by which it is secured to the gear housing and case E. The gear case is rectangular in form and carries the various gears and chains for reducing the speed of the motor M and transmitting the power to the feed screw or worm F.
- 15 The motor M is mounted onto the top end of the gear housing and is connected with a belt engaging over a sheave wheel on the motor shaft and over a sheave wheel mounted on a shaft extending from a reduction gear housing E. The worm F is driven from the opposite side of the gear housing.
- 20 The hopper A of the device is set on a base 60 said base being secured to the feed pipe 8 by cutting away a portion 8a from the feed pipe and then welding the base 60 into that space with the top side of the base 60 below the level of the top side of the feeding worm F. Onto this base 60 I then mount my fuel agitating and feeding device which consists of a round plate 63 held 25 in position by a lug extending up from the base 60 into a socket 65 in the center of the bottom side of the plate. Around the outer perimeter of this plate I provide teeth or fingers 66 so arranged that they will contact every other convolution of the fuel feed worm F and the rotative power of the feed worm is transmitted to the plate 63 by these teeth slowly rotating the plate. Onto the bottom side of this plate 63 I provide 30 an annular flange 68 to hold the plate spaced above the level of the top of the plate 63 and through this flange I provide angled cuts 69 to allow any trapped fine coal to work its way out of the space under the plate. The top side of the plate 63 is provided with upstanding fingers 70 to engage in the coal in the hopper and cause the fuel to drop into the feeding worm F. The base 60 has a section 71 cut therefrom to accom-

modate the feed pipe as shown in Figure 8 of the drawings. The hopper A is then secured within the flange 72 on the top side of the base 60 and the hopper is formed in the shape of a cone with one element thereof vertical to allow 5 a free downward movement of the coal pressing down onto the feed worm and the plate 63 at all times and thus there is a continuous feed of fuel into the feed worm without any arching or clogging of the coal, no matter how wet or what the 10 condition of the coal may be. The top of the hopper is closed by a circular flanged casting 75 secured thereto and with an opening therethrough to allow for feeding of fuel into the hopper. A cover G is pivotally secured to the casting 75 over the opening and a locking handle 76 is provided for the cover to lock it in closed position after the hopper has been filled.

Having thus described my invention I desire to secure by Letters Patent and claim: 20

In a device of the class described, the combination of a box-like base forming an air chamber and having one side extended with semi-circular openings in the closed end thereof; a cover for said extended side to close the top thereof with like semi-circular openings therein in alignment with the openings in the base; an air feed pipe leading into one of said openings in the extended end; a fuel feed pipe leading into another of said openings with the end of the feed pipe formed into an inverted frusto-pyramidal fire pot with the top of the pot above the level of the side walls of the base; a square tuyère casting having the top flat and the side walls extending downwardly and outwardly on an angle 35 with the inner side of the sides to fit against the top of the base to seal the air chamber and form the top thereof and having spaced apart bosses on the under side of the flat top, said bosses to rest on the top of the fire pot to leave openings 40 between the tuyère casting and the fire pot for passage of air from the air chamber for combustion of the fuel; and a clean out pipe extended into the extended end of said base through which accumulated dust may be blown by the air pressure 45 from the air feed pipe when the cover of the clean out pipe has been removed.

FREDRICK H. FRIDENSTINE.
